UNITED STATES PATENT OFFICE.

EMIL ROMM, OF HILLTOP, WEST VIRGINIA.

DESIGN FOR A DISPLAY-RACK OR CHRISTMAS TREE.

50,077.

Specification for Design.

Patented Dec. 19, 1916.

Application filed October 27, 1916. Serial No. 128,136. Term of patent 14 years.

To all whom it may concern:

Be it known that I, EMIL ROMM, a citizen of the United States, residing at Hilltop, in the county of Fayette and State of West Virginia, have invented a new, original, and ornamental Design for Display-Racks or Christmas Trees, of which the following is a specification, reference being had to the accompanying drawing, forming part thereof.

The figure is a perspective view of a dis-

play rack or "Christmas tree" showing my new design.

I claim:

The ornamental design for a display rack or "Christmas tree" as shown.

EMIL ROMM.
